FIG. 4

UNITED STATES PATENT OFFICE

RICHARD J. O'BRIEN, OF DEPEW, NEW YORK, ASSIGNOR TO WAUGH EQUIPMENT COMPANY, OF DEPEW, NEW YORK, A CORPORATION OF MAINE

SPRING-PLANK CUSHION

Application filed July 25, 1929. Serial No. 380,824.

This invention relates to a spring plank cushion for railway cars and the like, and it is an object of this invention to provide cushioning means for the plank that supports the spring of a car or the like and limits the expansion of the cushion so that it will always be effective for presenting a good yield and cannot become distorted and lifeless.

In cars used for transporting passengers, noises, vibrations and shocks resulting from contact of the wheel treads and flanges with the running rails are transmitted from the rails up thru the wheels, parts of the truck to the car underframe and body. This invention is designed to eliminate the transmission of such shocks and vibrations thru the spring plank.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

Figure 1 is a fragmentary end elevational view of a railroad car showing parts in section and involving this invention.

Figure 2 is an enlarged sectional view through the spring plank and hanger thereof.

Figure 3 is an enlarged plan view of the cushioning means.

Figure 4 is a part sectional and part elevational view illustrating the cushioning element at the top of the spring plank hanger.

In connection with this invention, there is shown in Figure 1 a part 1 of the truck structure which supports the usual hanger 2 which carries a spherical bearing block 3 at its lower end. A bearing plate 4 having a concave recess for receiving the convex bearing portion of the block 3 is supported upon said block 3 for swiveling movement and one end of the spring plank 5 is supported upon the block 4. It will be noted that the other end of the spring plank 5 is supported by a similar hanger 2, and that the spring plank 5 has depending flanges 6 and 7 between which the bearing block 4 is located.

According to this invention, an expandible

cushion element 8 is interposed between the block 4 and the spring plank 5, and is so designed with respect to the flanges 6 and 7 that they limit the expanding movement of the cushion in order that it may always present a good yield without losing its resiliency. While the pad 8 may assume any convenient form, it preferably consists of a center plate 9 with an oblong rubber ring 10 or the like molded upon each side thereof with a central rubber piece within each oblong ring. The dimension of the rubber piece 11 is such as to allow the ring 10 to properly expand when pressure is applied upon the cushion. While the drawings show a cushion under only one end of the spring plank, it will be understood that a similar cushion is placed under the other end.

In Figure 4, a cushion retainer 12 is secured upon the frame member 1 and an expandible rubber cushion 13 is confined within the retainer. A plate 14 is superposed upon the cushion 13 for supporting the rod 2^a of the hanger 2, so that the spring plank is resiliently supported.

It will be noted that the flanges 6 and 7 limit the expandible movement of the rubber ring 10 on each side of the plate 9, and in addition to preserving a good yield, the cushion is preserved against distortion and wear and tear.

I am aware that numerous details of construction may be varied through a wide range without departing from the principles of this invention, and I therefore do not propose limiting the patent granted, otherwise than necessitated by the prior art.

I claim as my invention:

1. In a railway car, a spring plank, a hanger for supporting one end thereof, and resilient cushion means comprising a central plate with nested and spaced blocks and rings of rubber secured to the opposite sides of the plate, the cushion means being located between said spring plank and hanger.

2. In a railway car, the combination with a spring plank, a hanger for supporting one end thereof, bearing members carried by said hanger, and expandible rubber elements interposed between said bearing and the spring

plank, and means for confining said element for a predetermined expansion.

3. In a device of the character described, the combination with a spring plank, of supporting means therefor, resilient cushioning means between said plank and supporting means, and means for limiting the expandable movement of said resilient means.

4. In a car of the character described, a hanger, bearing members supported by said hanger, a spring plank having flanges supported on said bearing member, and expandable rubber elements between said plank and bearing member and limited in expansion by said flanges.

10 In testimony whereof I have hereunto subscribed my name at Chicago, Cook County, Illinois.

RICHARD J. O'BRIEN.
